UNITED STATES PATENT OFFICE.

WILLIAM P. KING, OF SYRACUSE, NEW YORK.

LOCKING MECHANISM.

Application filed January 18, 1927. Serial No. 160,920.

This invention relates to means for locking covers, doors, and the like, and has especial reference to a power controlled locking device, designed particularly for use in connection with laundry extractors and other power operated machines.

The primary objects of the invention is to provide a safety device for extractors and other machines, which is controlled in part by the power that operates the extractors, and which positively and automatically holds the cover of the extractor in the closed position, and prevents access to the interior of the machine, as long as the power is "on".

15 A further object is to provide a locking device, which may be positively connected with the cover, and so arranged that when the power is shut-off and the cover is moved to the open position, the said device, with the cooperation of the cover, prevents the power from being turned on again, until the cover is closed. A further object is to provide a cover controlling mechanism, one member of which is driven directly by the power 20 that operates the extractor or other machine, the other member being operated by the movements of the cover, the arrangement of said members being such that, when the cover is closed and the extracting mechanism 25 is being operated, the said members are disconnected, and any attempt to open the cover causes the driven member to resist said opening movement and prevent access to the interior of the extractor, until the power is shut off. A further object is to 30 provide means for adjusting one of said members. And a further object is to provide simple means for simultaneously operating the extractor and the locking mechanism by the same power, and by the use of a common control.

The various features and parts of the invention will be understood from the detailed description which follows, and by reference 45 to the accompanying drawings, in which—

Figure 1 is a top plan view of a laundry extractor, to which my locking mechanism is applied, the cover of the extractor being closed. Fig. 2 is a side elevation of the same; the full lines showing the cover held in the closed position by the locking mechanism, the dotted lines showing the cover in the open position, and the locking mechanism tilted at an angle that prevents turning on the power and starting the extractor until the cover is closed. Fig. 3 is an en-

larged top plan view of the locking mechanism, in the act of holding the cover in the closed position. Fig. 4 is a side elevation of the same, parts of the device being broken away for showing the locking position of the rack relatively to the pinion when the cover is closed; also showing means for adjusting the rack. Fig. 5 is an enlarged horizontal section, taken on line 5—5 of Fig. 4; showing the spring that enables the pinion to be partially rotated on the sleeve by the opening of the cover, following the shutting-down of the power. And Fig. 6 is a vertical cross-section taken 70 on line 6—6 of Fig. 3.

In the drawings, (Figs. 1 and 2), is shown conventionally a laundry extractor, which has been selected mainly for the purpose of describing in a clear and practical way, my locking mechanism, and comprises an upright cylindrical tub or body 2, in which is rotatably disposed the usual perforated metallic basket, as 3, in which the wet clothes are placed, the basket being rotated at high speed for extracting the moisture from the clothes by centrifugal force, in a well-known manner, by a shaft 3', which is fitted with a pulley 3^a. The tub 2 is mounted upon a base 2', and has a normally open top, the opening being surrounded by an annular part 2^b, and is usually closed by a cover, as 4, the said cover in the present showing being formed of woven wire, and being hinged by a member 4', between lugs 2^c, which are rigidly secured to the annular portion 2^b. The dotted lines in Fig. 2 show the open position of the cover. The power for driving the basket 3 may be derived from any suitable source, and may be transmitted by a belt 5, which operates a driving pulley 5', from which the belt may be shifted, by any means (not shown), to an idle pulley 5^a, for stopping the basket 3. The pulleys 5—5^a are mounted upon a shaft 5^b, which passes horizontally through an upright cylindrical body 6, in which are disposed a pair of miter-gears 6'—6^a (see Fig. 1) that are supported respectively by shaft 5^b, and an upright shaft 7 upon whose lower end is mounted a pulley 7', that drives the pulley 3^a, by means of a belt 7^a. The shaft 5^b preferably extends through the body 6, and upon its farther end is mounted a pulley 5^c. The pulleys 5' and 5^c are both rigid on shaft 5^b, so that both are positively driven while the basket is being operated, and when

the belt 5 is shifted to the pulley 5^a, all driving motion of the parts, except pulley 5^a ceases, and the operator may readily and safely lift the cover (see dotted position 5 Fig. 2), remove the dry clothes, and refill the basket, without incurring any danger. The foregoing describes in a general way, the construction and arrangement of several well-known laundry extractors, all of which, 10 as a rule, are equipped with hinged or removable covers, but so far as I am aware, but few of these machines have been provided with any means whereby the covers may be locked or otherwise securely held in 15 closed position while the baskets are being operated. The lack of any safeguards against the lifting or opening of the covers of the tubs while the power is "on", has resulted in many accidents to careless or ignorant operators, and the authorities of some 20 of the States are demanding that all extractors be equipped with some practical means for remedying the said defects and obviating all said dangers in future. To 25 this end, I have devised novel and simple means, whereby the cover as 4, cannot be opened as long as the power is "on" and the basket 3 is in motion, and the said means furthermore automatically prevents the 30 power being turned on for starting the basket, while the cover is in the opening position. A detailed description of my invention follows:

8 represents a counter-shaft, which may 35 be supported by any suitable hangers (not shown). Upon one end of said shaft is mounted a pulley 8', which is shown driven by the pulley 5^a, and a belt 8^a. 9 represents a sleeve, which is preferably rigidly mounted 40 on the shaft 8 by a set-screw 9', the said sleeve being formed at one end with a head 9^c. 10 represents one of the locking members comprising a pinion having at one end a hub 10', the said parts being bored out to 45 operatively fit the sleeve 9, and the hub being provided with a circumferential slot 10^a. The gear 10 is driven by the shaft 8 in the direction indicated by the circular arrows 50 in Figs. 4 and 6, by a screw-stud 9^e, which is located and plays in the slot 10^a. The gear 10 is rotatable on the sleeve 9 in the reverse direction, to the extent of the length of the slot 10^a, as will be explained later on. The opposite end of the pinion 10 is counterbored, as at 10^b, and in this cavity is disposed 55 a stout spiral spring 12, whose ends are respectively secured to the sleeve 9, and the pinion 10, as indicated at 10^c, in Figs. 4, 5 and 6. By this arrangement, the spring 60 12 tends to hold the pinion in the driving position, with the stud 9^e engaging the corresponding end of the slot 10^a (see Fig. 5). The sleeve 9 and the pinion 10 are enclosed 65 by a casing 13, and a correspondingly shaped cap 13', the latter being held in place by

screws 13^a. The top of the casing 13 is formed with a hollow horizontal guide portion 13^b (see Figs. 1, 2, 3 and 4), whose guide-way 13^d is disposed in the path of or tangent to the uppermost teeth of the pinion 10. The normally open rear side of the guide 13 is closed by a correspondingly shaped portion 13^e of the cap 13'. The second locking-member consists of a relatively long bar 14, whose medial portion has its lower edge formed with teeth 14', that are arranged to engage the teeth of the pinion, when the bar is moved towards the right, according to the showing in Fig. 4. One end 14^a of the bar extends beyond the teeth 10^a-14' and is preferably reduced to the extent of the depth of the teeth (see Fig. 4). The opposite end 14^b of the rack 14 is arranged to pivotally connect with a lug or arm 4^a, which is preferably integral to the hinge member 4' of the cover. The end 14^b of the rack is preferably split (see Figs. 2, 3 and 4) for providing a separate and movable part 14^c, which is directly connected to the lug 4^a. The reduced portions of the bar 14 and the part 14^c are adjustably held in place by screws 14^a, the said screws being applied from the opposite edges and being arranged to play in slots 14^e, which enable the part 14^c to be moved towards and away from the arm 4^a, in a well-known manner. The facing edges of the parts 14^b and 14^c are preferably corrugated (see Fig. 4), for preventing twisting or slippage of the parts. The arm 4^a preferably extends a considerable distance above the perforated lugs 2^b of the tub, so that when the power is shut-down and the cover is raised, as shown by dotted lines in Fig. 2, the arm 4^a freely moves the rack-bar 14 towards the locking mechanism carried by the shaft 8, and rotates the pinion 10 on sleeve 9, against the tension of spring 12. This reverse rotation of the pinion is allowed by the slot 10^a, as explained. When my locking mechanism is applied to an extractor or other machine, the part 14^c is preferably so adjusted that when the cover, as 4, is fully open, as shown in Fig. 2, the arm 4^a swings the rack bar 14 downwardly (see dotted lines in Fig. 2) at such an angle as to effectually prevent the rotation of the pinion, by the power, until the cover has been lowered manually to the closed position. By this construction and arrangement, as long as the cover is in the open position, it is impossible for the operator to turn on the power for starting the extractor, and rotating the pinion 10, for the reason that the rack 14 being in positive mesh with the pinion, must first be moved towards the extractor until its teeth are free from the teeth 10^a, before the pinion may be rotated by the power, as shown in Fig. 4. In case the operator attempts to start the extractor while the cover is open,

the resistance offered by the rack and arm 4^a, as explained, will either stall the whole unit or else simply cause the belt 8^a to slip on the pulleys 5^c and 8'. When the cover 5 is closed, the spring 12 recoils and assists the arm 4^a to move the rack 14 endwise until the last of the teeth 14' clears the teeth 10^d of the pinion, as shown in Fig. 4. This clearance is preferably so calculated, when 10 the rack bar is properly adjusted, as to position the last tooth of the rack about one thirty second of an inch clear of the teeth 10^d. This finally disposes of all resistance and obstruction to the free rotation of the 15 pinion 10, while the basket 3 is being rotated another extracting period. In case the operator or others attempts to raise the cover 4, while the basket is in motion, the first slight endwise movement of the rack 14 20 away from the extractor brings the nearest tooth 14' into engagement with the pinion, and the latter owing to its rapid rotation and the frequency of the teeth 10^d instantly exerts the full force of the power for thrusting the rack in the opposite direction for 25 restoring the cover to its fully closed position, as shown in Figs. 1, 2 and 4. The pinion 10 is usually operated at 600 to 800 R. P. M., and this high speed when supplemented by the power, is sufficient to resist the strength of the operator, with the result 30 that the cover remains tightly closed until the power is again shut down.

Having thus described my invention, what

35 I claim, is—

1. In a locking mechanism for power driven laundry extractor and the like, the combination with the cover of the extractor, and a source of power, of a pinion adapted 40 to be driven by said power, and a rack bar connected to said cover adapted to be held free from said pinion while the cover is closed, said rack adapted to engage the teeth of the pinion at the initial opening movement 45 of the cover, and said pinion adapted to prevent the opening of the cover while the extractor and said pinion are being driven by said power.

2. The combination with a driven mechanism having a protecting cover or like part, a bar connected to said cover and controlling the opening thereof, a member driven by the power that drives said mechanism adapted 55 to prevent the movement of said bar in the direction for effecting opening of the cover while the power is on, said cover and said bar adapted to drive said member in the opposite direction by the opening movement of the cover and to prevent the operation 60 of said member by the power as long as the cover remains open.

3. Means for locking the cover of a laundry extractor during the operation of the extracting mechanism, including a source of power, a reciprocatable and rockable member

connected to and operable by the opening and closing movements of the cover, a second member rotatable by said power adapted to prevent the movement of the first member for opening the cover, means for shutting off the power and stopping the said mechanism, and means for tilting the first member for preventing the starting of the extractor mechanism and said second member while the cover remains open.

4. The combination with a laundry extractor, a cover for closing the normally open top of the extractor body, and a source of power for operating the extractor, of a reciprocatable bar for controlling the opening of said cover, and a rotatable member adapted to be driven by said power, said bar connected to and adapted to be reciprocated by said cover when the power is shut-off, said member adapted when rotated by the power 85 to prevent the reciprocation of said bar, and said cover and said bar adapted to jointly prevent the operation of the extractor and said member while the cover is in the open position.

5. The combination with a power driven mechanism protected by a hinged cover, of means for holding said cover in the closed position while said mechanism is being operated comprising a pinion adapted to be driven by said power, and a bar movable tangentially towards said pinion, one end of said bar being pivoted to said cover, the opposite end portion of the bar having teeth adapted to mesh with the teeth of the pinion when the cover is moved towards the open position, said pinion adapted when rotated by the power to prevent the meshing of said teeth and the opening of the cover, and said bar adapted to be tilted by the opening movement of said cover for preventing the power from operating the pinion until the cover is closed.

6. In a locking mechanism for power driven laundry machines and the like, the combination with a hinged cover, the hinged member having an arm, of a rack bar connected to said arm, a pinion adapted to be driven in one direction by said power, a spring for resiliently holding the pinion in the driving position, a casing supporting said pinion, said casing having a guide-way to receive said rack bar adapted to guide said bar across the path of said pinion, said pinion adapted to prevent movement of said rack bar in the direction for opening said cover while said pinion is being rotated by the power, and said cover adapted to move said rack bar into engagement with and to rotate said pinion in the opposite direction against the tension of said spring while the cover is being opened.

7. The combination with a laundry extractor having a hinged cover, and a source of power for operating said extractor, of a

locking member adapted to be driven by said power, a second member in constant engagement with said cover and movable towards and away from the first member by the opening and closing of the cover when the power is shut-off, said first member when driven by said power being rotatable towards the second member and adapted to prevent the opening of said cover, and said cover adapted when fully opened to dispose the second member at such an angle as to prevent the operation of the first member by the power until the cover is closed.

8. The combination with a power driven machine and a manually operable part of said machine, of means for preventing the manual operation of said part including a rack connected to and movable towards and from the machine by the movements of said part, a pinion adapted to be driven by the power that actuates said machine, said pinion adapted to prevent movement of said rack while the power is on, said pinion adapted to yield for enabling said part to be manually operated when the power is shut-off, and said part adapted to cooperate with said rack for preventing the power from operating the machine and said pinion until said part is restored to its normal position.

9. In a lock for the cover of a power operated extractor, a rack pivoted at one end to the cover, a guide for supporting the opposite end of the rack, a pinion driven by the power that actuates the extractor, the teeth of the pinion extending into the guide adapted when driven by the power to pre-

vent said rack from being moved endwise for enabling said cover to be opened, means for shutting off the power for stopping the extractor and said pinion, means for enabling said rack to rotate the pinion in the opposite direction by the opening movement of the cover following the shutting off of the power, and means for preventing the power from starting the extractor while the cover remains open.

10. The combination with a laundry extractor having a hinged cover and a source of power for operating the extractor, of means for locking the cover in the closed position while the extractor is being driven by the power comprising a pinion adapted to be rotated by said power during the extracting intervals, means for shutting off the power for stopping the extractor and said pinion, and a member interposed between the pinion and said cover adapted to be held out of contact with the pinion by the cover when the latter is closed, said member adapted to be thrust towards the extractor by the pinion whenever the cover is moved towards the open position while said pinion is being driven by the power, said member adapted to engage and rotate said pinion in the opposite direction by the opening movement of the cover when the power is shut-off, and said member being arranged to be tilted by said opening movement for preventing the starting of the extractor while the cover remains open.

In testimony whereof I affix my signature.
WILLIAM P. KING.
